UNITED STATES PATENT OFFICE.

T. AVERY LONG, OF HOWARD, PENNSYLVANIA.

VEHICLE HEATER AND LAMP.

SPECIFICATION forming part of Letters Patent No. 363,149, dated May 17, 1887.

Application filed February 8, 1887. Serial No. 226,934. (No model.)

To all whom it may concern:

Be it known that I, T. AVERY LONG, a citizen of the United States, residing at Howard, in the county of Centre, State of Pennsylvania, have invented certain new and useful Improvements in Vehicle Heaters and Lamps, of which the following is a specification, reference being had therein to the accompanying drawings.

10 This invention relates to certain improvements in vehicle heating and lighting lamps; and it has for its objects to provide a lamp for the above-named purpose that will be cheap and simple, as well as durable. These objects 15 I attain by the means illustrated by the accompanying drawings.

Figure 1 represents a vertical section of my invention attached to the floor of a vehicle; Fig. 2, a perspective view of the lamp-holding receptacle; Fig. 3, a perspective view of the lamp without the globe and burner; Fig. 4, a view of the flame-shield.

In the drawings, the letter A indicates the bottom or floor of a vehicle, through which has 25 been cut an opening, a, suitable to receive the lamp-holding receptacle B, which is provided with an annular flange, b, by which the receptacle is hung, and an opening, I', in front, as plainly indicated in the drawings. The top 30 of the receptacle is provided with a hinged cover, d, provided with apertures g, for the purposes hereinafter described.

The lamp is constructed with an oil-cup, C, and provided with an ordinary burner and 35 globe of the tubular construction, the said globe being held in position by the wire frame D, consisting of a ring, E, that fits over the top of the globe, and has pivotally connected to it the vertical wires F F G G, the wires F F 40 being also pivoted to the oil-cup by the loop A, and the wires G G are detachably connected to the cups by the hook I. A flame-shield, K, is attached to the top of the globe by the spring-wires m attached to it.

45 The usefulness and objects of my invention can plainly be seen from the description of the operation, as follows: The lamp-receptacle is

suspended in the opening of the vehicle, the lamp lighted, the different parts adjusted thereto and placed in position in said receptacle. The heat from the lamp passes upward through the apertures in the cover, warming the occupants of the vehicle, of course supposing them to be using lap-robles, under which the heat is retained. At night the light from 50 the lamp shines through the opening in the front of the receptacle, lighting the road in front of the vehicle, and, if desirable, the opening in front may be provided with an ordinary dark-slide. 55

The wire frame is for the purpose of holding the globe of the lamp steady and to prevent its falling off. The lamp itself fitting snugly within the receptacle, prevents it from tipping or otherwise moving, and to remove 60 the globe the frame is simply unhooked at one side and thrown upward and backward.

The wire chimney-holder, being loosely connected to the lamp, has a play independent thereof, which permits it to withstand the 70 shocks due to rough travel and from inclining when the vehicle tips, so that the chimney will not become smutted or broken by sudden heating, which would be the case otherwise.

Having thus described my invention, what I 75 claim, and desire to secure by Letters Patent, is—

1. The combination, with the suspended receptacle having a hinged perforated top, of the lamp having a loosely-connected wire 80 chimney-holder, whereby the chimney is permitted to have an independent motion to provide against shocks, substantially as specified.

2. The combination, with the suspended receptacle, of the lamp, its loosely-connected 85 chimney-holder, and the flame-shield detachably secured to the top of said holder, substantially as specified.

In testimony whereof I affix my signature in presence of two witnesses.

T. AVERY LONG.
